UNITED STATES PATENT OFFICE.

ROY E. JORDAN, OF NEWARK, NEW JERSEY, ASSIGNOR TO THE MOSAIC TILE COMPANY, A CORPORATION OF OHIO.

DESIGN FOR A RECESSED SOAP DISH.

Application filed March 4, 1924. Serial No. 8,818. Term of patent 14 years.

To all whom it may concern:

Be it known that I, ROY E. JORDAN, a citizen of the United States, residing at Newark, county of Essex, and State of New Jersey, have invented a new, original, and ornamental Design for Recessed Soap Dish, of which the following is a specification, reference being had to the accompanying drawing, forming part thereof.

Fig. 1 is a perspective view of a recessed soap dish embodying my invention;

Fig. 2 is a front elevation of said dish;

Fig. 3 is a side view thereof; and

Fig. 4 is a plan view of the same.

I claim:

The ornamental design for a recessed soap dish, as shown.

ROY E. JORDAN.
